(57) **CLAIM**

We claim the ornamental design for a multifunction printer, as shown.

DESCRIPTION

FIG. 1 is a right-front-top perspective view of the multifunction printer of the present invention, showing a new design;

FIG. 2 is a front elevational view thereof;

FIG. 3 is a back elevational view thereof;

FIG. 4 is a left side elevational view thereof;

FIG. 5 is a right side elevational view thereof;

FIG. 6 is top plan view thereof;

FIG. 7 is a bottom plan view thereof; and,

FIG. 8 is a left-front-bottom perspective view.

The broken lines in the figures show an environment of the multifunction printer that forms no part of the claimed design. The shade lines in the figures show contour and not surface ornamentation.
